US00D961602S

(12) **United States Design Patent** (10) Patent No.: **US D961,602 S**
Watanabe et al. (45) Date of Patent: **** Aug. 23, 2022**

(54) **DISPLAY SCREEN OR PORTION THEREOF WITH GRAPHICAL USER INTERFACE**

(71) Applicant: **Roland Corporation**, Shizuoka (JP)

(72) Inventors: **Yasuyuki Watanabe**, Shizuoka (JP);
Atsushi Hoshika, Shizuoka (JP);
Makoto Mitsumori, Shizuoka (JP)

(73) Assignee: **Roland Corporation**, Shizuoka (JP)

(**) Term: **15 Years**

(21) Appl. No.: **29/767,162**

(22) Filed: **Jan. 21, 2021**

(30) **Foreign Application Priority Data**

Jul. 30, 2020 (JP) ..... 2020-015818 D

(57)

CLAIM

The ornamental design for a display screen or portion thereof with graphical user interface, as shown and described.

DESCRIPTION

The FIGURE is a front view of a display screen or portion thereof with graphical user interface showing our new design.

The dot-dash broken line illustrates the display screen or portion thereof that forms no part of the claimed design.

1 Claim, 1 Drawing Sheet
